US00D783329S

(12) **United States Design Patent** (10) **Patent No.:** **US D783,329 S**
(45) **Date of Patent:** **** Apr. 11, 2017**

(54) **TABLE BASE**

(71) Applicant: **Liberty Procurement Co. Inc.**, Union, NJ (US)

(72) Inventor: **John Merritt**, Brooklyn, NY (US)

(73) Assignee: **Liberty Procurement Co. Inc.**, Union, NJ (US)

(**) Term: **15 Years**

(21) Appl. No.: **29/527,682**

(22) Filed: **May 21, 2015**

(51) LOC (10) Cl. **06-06**

(52) U.S. Cl.

USPC **D6/708**

CLAIM

The ornamental design for a table base, as shown and described.

DESCRIPTION

FIG. 1 is a perspective view of a table base;

FIG. 2 is a right-side elevation view thereof;

FIG. 3 is a left-side elevation view thereof;

FIG. 4 is a front elevation view thereof;

FIG. 5 is a back elevation view thereof;

FIG. 6 is a top plan view thereof; and,

FIG. 7 is a bottom plan view thereof.

The broken lines shown in the drawings are for the purpose of illustrating environmental structure and form no part of the claimed design.

1 Claim, 6 Drawing Sheets
